UNITED STATES PATENT OFFICE.

MARTIN McDONALD, OF WASHINGTON, DISTRICT OF COLUMBIA.

DOORKNOB FASTENING.

Application filed December 13, 1921. Serial No. 522,021.

To all whom it may concern:

Be it known that I, MARTIN McDONALD, a citizen of the United States, residing at Washington, in the District of Columbia, have invented new and useful Improvements in Doorknob Fastenings, of which the following is a specification.

This invention relates to door knobs and more particularly to means for fastening the knob to the spindle, and has for its object to provide certain new and useful improvements in the construction shown in my prior Patent No. 1,128,339, issued February 16, 1915. The particular feature of invention set forth in the present case is the construction whereby the formation of the ratchet teeth on the interior of the knob shank is simplified and rendered inexpensive.

20 In the drawings:—

Figure 1 is a longitudinal sectional view taken through a door knob and the adjacent end portion of a spindle having my invention applied thereto.

25 Figure 2 is a cross sectional view on the line 2—2 of Figure 1.

Figure 3 is a view similar to Figure 2, the spindle and dog or detent being omitted.

Figure 4 is a perspective view of one 30 end of the spindle.

Figure 5 is a detail perspective view of the double dog or detent which is carried by the spindle.

As shown in the accompanying drawing, 35 1 designates a spindle, and 2 designates a knob of any common or preferred form or construction. The spindle is rectangular in cross section, as usual, and the tubular shank 3 of the knob is provided with a rectangular bore 4, as usual, to receive one end portion 40 of the spindle.

As in my prior patent, the spindle 1 is provided in each end with an opening or slot 5 extending transversely therethrough 45 and disposed longitudinally of the spindle for a suitable distance. Within this opening there is mounted a double dog or detent 6, one end of which is pivotally mounted upon a pin 7 carried by the spindle and 50 extending transversely across the opening 5 adjacent the inner end thereof. The dog shown in the accompanying drawing is formed from a single piece of spring metal which is bent intermediate of its ends into substantially U-shape, and the end portion 55

of each side or leg of the dog is bent back upon itself to form a ratchet finger 8, the extremity of which flares outwardly from the U-shaped body or shank of the dog. The dog may be conveniently assembled 60 with the spindle by placing the dog astraddle of the pin 7 and then turning the dog into the opening 5 in longitudinal alignment therewith. The ratchet fingers 8 extend outwardly through the open sides of 65 the slot or opening 5 and slightly beyond the slotted faces of the spindle, as clearly indicated in Figure 1 of the drawing.

The knob shank 3 is split longitudinally as at 9, and also at right angles thereto as 70 at 10, thereby producing two longitudinal slots or bifurcations intersecting one another at substantially right angles, and also intersecting the end of the shank 3 opposite the knob 2.

75 Ratchet teeth 11 are formed on the walls of the bore 4 of the knob shank 3, and these teeth are cut by means of a suitable tap introduced through the open end of the bore, and therefore it will be understood that 80 the ratchet teeth 11 are in the nature of a screw thread cut on the eight corners of the bore 4, which corners are formed by the intersections of the slots 9 and 10 with the walls of the bore. The operation 85 of cutting the ratchet teeth by means of a tap is a very simple and inexpensive one, and at the same time the ratchet teeth are formed in a very simple and efficient manner.

90 In assembling the parts of the device, a dog or detent 6 is mounted within each end of the spindle 1 and the latter thrust endwise through the lock of the door with its ends projecting at opposite sides of the door, 95 the door being indicated at 12 in Figure 1 of the drawing. The usual face plate or escutcheon is indicated at 13. The knob and its shank 3 are then assembled upon one end of the spindle 1 by receiving the latter 100 endwise through the open end of the bore 4, the ratchet teeth being engaged by the free end portions 8 of the dog or detent 6 over which end portions the ratchet teeth slip until the end of the knob-shank is in close 105 proximity with the adjacent face of the door of the escutcheon plate 13, at which point the free extremities 8 of the dog snap into engagement with adjacent ratchet teeth and hold the knob shank 3 snugly upon the 110

spindle. As the spindle 1 and the bore of the shank 3 are rectangular in cross section and fit one another with comparative snugness, rotation of the knob will of course 5 result in rotation of the spindle, but the knob is prevented from being pulled endwise from the spindle by reason of the engagement of the dog with the ratchet teeth of the knob shank, and therefore the knob 10 will be effectually and rigidly held upon the spindle in a very simple and efficient manner. The knob may be fitted to any desired adjusted position upon the spindle, as the ends of the dog will cooperate with 15 the ratchet teeth at any point along the bore of the knob shank. The knob may be removed from the spindle by disengaging the free end portions of the dog from the ratchet teeth which will leave the knob shank free 20 from the spindle and in which condition it may be readily moved endwise from the spindle. The slot or bifurcation 9 gives access to the free extremities of the dog for convenience in disengaging the latter from 25 the ratchet teeth of the knob shank.

It will of course be understood that each end of the spindle is provided with a dog, and when the spindle has been placed in a door, the knobs may be very conveniently 30 fitted to the respective ends of the spindle and adjusted thereon in accordance with the thickness of the door.

It will be noted that so far as external appearance is concerned, there is little or no 35 change in the knob and spindle, but at the same time the fastening is effectually housed and protected within the shank of the knob. The knob may be very conveniently fitted to the spindle and adjusted lengthwise thereon, 40 and also may be conveniently removed. Looseness of the knob is absolutely prevented by reason of the two ratchet fingers engaging opposite sides of the bore of the shank.

45 An important improvement over my prior patent resides in the fact that each of the bifurcations or slots 9 and 10 extend through or intersect the end of the shank opposite the knob whereby the free extremities of 50 the dog or detent are always accessible through one or the other of the bifurcations and therefore there is no position in which the free ends of the dogs are not accessible and capable of being disengaged from 55 the ratchet teeth.

The prime purpose of employing two slots or bifurcations 9 and 10 at substantially right angles to one another is that one of the slots will always register with the opening 5 in the spindle 1, and therefore it is 60 unnecessary to take any great care to see that the knob and its shank are placed upon the spindle in any predetermined position. In other words, when the knob shank is on 65 the spindle there is always a slot or bifur-

cation in the shank which exposes the free ends of the dogs for convenience in disengaging the same from the ratchet teeth.

Having thus described the invention what is claimed is:

1. The combination of a spindle and a knob having a shank, the spindle being provided with a longitudinal slot, a double dog mounted in the slot with its extremities projecting at opposite sides of the spindle into engagement with opposite walls of the bore of the knob shank, the knob shank being provided with longitudinal bifurcations intersecting one another at substantially right angles, and the bore of the shank having ratchet teeth tapped therein and engaged by the free ends of the double dog. 75

2. The combination of a door spindle provided with ratchet fingers projecting at opposite sides thereof, and a door knob having a shank provided with a bore receiving the spindle, the shank being provided with longitudinal bifurcations intersecting one another at substantially right angles, and the bore of the shank having ratchet teeth tapped therein and engaged by the ratchet fingers. 80

3. The combination of a spindle provided with ratchet fingers at opposite sides thereof, and a door knob having a shank provided with a longitudinal bore receiving the spindle, said shank also being provided with longitudinal bifurcations intersecting one another at substantially right angles, the bore of the shank being provided with a screw thread cut along the edges of the bore defined by the walls of the bore and the walls of the bifurcations, said screw thread constituting ratchet teeth in cooperative relation with the ratchet fingers. 95

4. The combination of a door spindle provided with ratchet fingers projecting at opposite sides thereof, and a door knob having a rigid shank provided with a bore receiving the spindle, the shank being provided with longitudinal bifurcations intersecting one another, and the bore of the shank being provided with ratchet teeth engaged by the ratchet fingers, one of the bifurcations being in alignment with the ratchet fingers to give 100 access thereto for disengaging them from the ratchet teeth. 110

5. The combination of a substantially rectangular door spindle provided with ratchet fingers projecting at opposite sides thereof, and a door knob having a rigid shank provided with a substantially rectangular bore receiving the spindle, the shank being provided with longitudinal bifurcations intersecting one another at substantially right angles, the bore of the shank being provided with ratchet teeth engaged by the ratchet fingers, and one of the bifurcations being in alignment with the ratchet fingers 115 and exposing them for access for conven- 120

ience in disengaging the fingers from the ratchet teeth.

6. The combination of a door spindle provided with a ratchet finger, a door knob having a rigid shank provided with a bore receiving the spindle, said bore having ratchet teeth engaged by the ratchet finger, and said shank being provided with a longitudinal slot intersecting the end of the shank opposite the knob and extending throughout the toothed portion of the bore.

7. The combination of a door spindle provided with a ratchet finger, a door knob having a rigid shank provided with a bore receiving the spindle, said bore having ratchet teeth tapped therein and engaged by the ratchet finger, and said shank being provided with a longitudinal slot intersecting the end of the shank opposite the knob and extending throughout the toothed portion of the bore.

8. The combination of a door spindle provided with a ratchet finger, a door knob having a rigid shank provided with a bore re-

ceiving the spindle, said bore having ratchet teeth tapped therein and engaged by the ratchet finger, and said shank being provided with longitudinal slots intersecting the end of the shank opposite the knob and extending throughout the toothed portion of the bore.

9. As a new article of manufacture, a door knob having a rigid shank provided with a bore to receive a spindle, said bore having ratchet teeth tapped therein, and the said shank being provided with a longitudinal slot intersecting the end of the shank opposite the knob and extending throughout the toothed portion of the bore.

10. As a new article of manufacture a door knob having a shank provided with a bore for receiving a spindle, said shank being provided with longitudinal bifurcations intersecting one another at substantially right angles, the bore of the shank having ratchet teeth tapped therein.

MARTIN McDONALD.
